LUBRICATING OIL REFINING

James H. Shepard, Casper, Wyo., assignor to
Standard Oil Company, Chicago, Ill., a corpora-
tion of Indiana

Application January 11, 1933, Serial No. 651,092

4 Claims. (Cl. 196—13)

This invention relates to the refining of lubricating oil and it pertains more particularly to the use of special solvents for separating paraffinic from naphthenic constituents of mixed base lubricating stocks whereby the viscosity index of the finished lubricant is improved.

My process relates to the use of a selective solvent such as beta beta dichlorethyl ether, and the object of my invention is to improve the efficiency of solvent extraction processes in which such a solvent is used. A further object is to increase the yield of my high viscosity index oil from any given stock. A further object is to reduce the amount of solvent required per gallon of finished oil produced. A further object is to avoid emulsion difficulties, and particularly to avoid the conventional step of soap removal after the neutralization which follows a preliminary acid treatment. A further object is to reduce corrosion, both in the solvent extraction step and in the condenser coils wherein the solvent is recovered. A further object is to reduce the cost of neutralization as well as the cost of diluent, oil, etc. A further object is to provide an improved lubricating oil which will be characterized by a low ash and a high color stability, and which will have a minimum tendency to form emulsions (high demulsibility). Other objects will be apparent as the detailed description of my invention proceeds.

In practicing my invention, I first give my lubricating stock a light acid treatment and separate the sludge and tarry matter therefrom. I then neutralize the sour oil with ammonia and I do not attempt to wash out the ammonia soaps but leave them in the oil solution. I next extract the oil with about two and one-half to three volumes of beta beta dichlorethyl ether or the like, separating the extracted layer from the raffinate layer, and removing the solvent from both layers. Finally, I treat the raffinate with clay to obtain the desired color and to remove any undesirable soaps which may have remained in the oil. It should be particularly noted that in this process the soaps formed from the sulfonic and other oil soluble acids (mahogany acids) in the neutralization following the preliminary acid treat, are thrown down with the extract in the solvent extraction step so that I avoid the removal of ammonia soaps prior to the extraction step.

The invention will be more clearly understood from the following detailed description and from the accompanying drawing which forms a part of this specification and which shows a diagrammatic plan of my improved system.

I will describe the invention as applied to the treating of a heavy distillate lubricating stock which has been dewaxed and which has a viscosity of about 80 seconds Saybolt at 210° F. It should be understood, however, that the invention is equally applicable to stocks which have not

been dewaxed, to residual stocks and, in fact, to any lubricating oil stock prepared from mixed base naphthenic or asphaltic crudes. If and when a residual stock is used, it may be desirable to remove the bulk of the asphaltic material by a preliminary precipitation thereof with propane, or by a heavier acid treat than that which is hereinafter described. Such expedients will be apparent to those skilled in this art.

As the extracting solvent I prefer to use beta beta dichlorethyl ether which will hereinafter, for the sake of simplicity, be referred to as "ether". I may, however, use other solvents, such as chloraniline, nitrobenzene, aniline, paraldehyde, furfural, cresol, pyridine, phenyl acetate, ethyl chloracetate, isopropyl ether, furfuralcohol, etc., or mixtures thereof.

The oil stock from storage tank 10 is forced by pump 11 through mixer 12, where it is intimately mixed with acid supplied from acid tank 13 and introduced by pump 14. This acid treatment is of a preliminary nature and it serves to remove a large amount of tarry matter and to thereby materially reduce the necessary amount of extracting solvent. I prefer to use about one-half to three-fourths pound of 93% acid per gallon of oil treated, but it should be understood that these proportions and concentrations may vary somewhat, depending upon the nature of said oil stocks.

The mixture of acid and oil is introduced by pipe 15 into continuous sludge separator 16, and sludge being removed at the base thereof through pipe 17 and the sour oil being removed from the upper part through pipe 18 to receiver 19. The separator may be a horizontal cylindrical tank or it may be an upright tank with a conical bottom. It may be preferable to effect sludge separation by centrifugal means and it should be understood that I may use a centrifuge instead of a settling tank for continuously removing the sludge from the sour oil.

The sour oil from receiver 19 is forced by pump 20 to neutralizer tower 21 wherein it passes countercurrent to ammonia vapors introduced at the base of the tower through pipe 22. The amount of ammonia introduced is just sufficient to neutralize the sour oil and I may, in fact, eliminate the neutralizer tower 21 entirely and merely blow the ammonia into the base of receiver 19. I prefer, however, to effect continuous neutralization in the manner hereinabove described, the neutralized oil being passed by pipe 23 to receiver 24.

The neutralized oil from receiver 24 is forced by pump 25 into mixer 26 wherein it is intimately mixed with about two and one-half to three volumes of "ether" introduced from storage tanks 27 by pump 28. It is essential that intimate contacts be obtained between the solvent and the

neutralized oil and I may use steam coils in addition to mixer 26 for heating the mixture above its miscibility temperature. To effect separation of paraffinic from naphthenic components the mixture must be cooled preferably to about 40° or 50° F., and I therefore pass the mixture through cooler 29 prior to introducing it into raffinate-extract separator 30. This separator may be of the simple gravity type or it may consist of a centrifuge or equivalent means for separating the heavy "ether" extract from the lighter raffinate phase. Ordinarily the raffinate and extract separate readily, but if there is a tendency toward emulsion formation, the centrifuge will solve the difficulty. The extract is discharged through pipe 31 to a suitable recovery system and the raffinate is discharged into receiver 32 from which it is picked up by pump 33 and forced into stripping still 34 for removing the solvent from the oil. The "ether" vapors are condensed in condenser 35 and returned by pipe 36 to storage tanks 27. In order to prevent decomposition of the "ether" in condensing coils I introduce a small amount of ammonia gas thereto through pipe 37. To remove the last traces of solvent from the oil in the still I prefer to strip with steam which may be introduced through pipe 38. The water which is thus mixed with the solvent may be removed therefrom by a suitable water trap 39.

The oil from the stripping still is next forced by pump 40 to contact clay filter 41, where the oil is percolated through fuller's earth and at a temperature of about 250-300° F. Alternatively, I may contact the oil with about one-half to three-fourths pound of clay per gallon at about 540° F. and then percolate to color. Ordinarily, however, the simple percolation step is sufficient. The finished oil is conveyed by pipe 42 to a suitable storage tank or, if the oil still contains wax, it is passed to a suitable dewaxing system.

An important feature of the process hereinabove described is the acid treatment of the oil prior to the solvent extraction step. The beneficial effects of this preliminary acid treatment may be obtained even if the oil is extracted with the "ether" prior to neutralization, but such a process would be objectionable because of the corrosion which would be encountered throughout the extraction system. In accordance with conventional practice, these corrosion difficulties would ordinarily be overcome by neutralizing the sour oil with caustic, using about 32 pounds of soda ash per thousand gallons of oil stock charged. After such neutralization it is necessary to extract the sodium mahogany soap from the neutralized oil, which step requires about 107 gallons of 10% green acid soap per thousand gallons of oil stock charged, causing a loss of 2-10% of the oil, or which requires a large amount of expensive alcohols or equivalent solvents. I avoid entirely the use of the green acid soap or equivalent solvent, and I materially reduce the cost of neutralizing reagents by using ammonia instead of soda ash. It has heretofore been considered impossible to obtain satisfactory neutralization with ammonia because the ammonium soaps cause emulsion difficulties, and because the ammonia neutralized oil was not color stable. I have discovered that when ammonia neutralization is followed by solvent extraction the objectionable ammonium soaps are removed with the extract,

and I have found that this separation may be readily effected without emulsion difficulties. Furthermore, I have found that when the raffinate is finished with clay, the oil has as good a color stability as oil produced from soda neutralized and washed stock. It will thus be seen that by ammonia neutralization I decrease the cost of the neutralizing agent, I eliminate entirely the steps of hot water washing and mahogany soap removal, and I facilitate handling. In addition to all of these advantages I find that the process hereinabove described gives a 2-10% higher yield than can be obtained with the conventional soda neutralization, a large part of this saving probably being due to the elimination of the hot water washing step in the extraction of mahogany soap.

The ammonia neutralization prior to solvent extraction not only minimizes corrosion in the solvent extraction system, but it reduces the amount of ammonia which would be introduced by pipe 37 into condenser coils 35. In other words, the use of ammonia neutralization minimizes the hydrolysis or decomposition of the "ether". As a matter of fact, I have found that the solvent loss in my ammonia neutralization process is about one-half to one-third the amount heretofore obtained and is reduced to about .01%.

While I have described in detail a preferred embodiment of my invention, it should be understood that I do not limit myself to the details hereinabove set forth except as defined by the following claims which should be construed as broadly as the prior art will permit.

I claim:

1. The process of refining mineral oils which comprises subjecting mineral oil stocks to treatment with sulfuric acid, separating the acid sludge from the oil, neutralizing the acid treated oil with ammonia, immediately (without the intervention of a water washing step) extracting the ammonia neutralized oil with a selective solvent of the type used for separating paraffinic from naphthenic components, separating an extract phase from a raffinate phase and removing solvent from each phase respectively.

2. The process of refining mineral lubricating oils which comprises treating said oils with a small amount of sulfuric acid, neutralizing said treated oil with ammonia, and without removing oil soluble or water soluble sulfonic compounds from the neutralized oil, extracting said oil with a solvent comprising at least one of the class which consists of beta beta dichlorethyl ether, chloranilene, nitro benzene, furfural, cresol, pyridine and furfuralcohol, separating a raffinate from an extract phase and separately removing solvent from each phase respectively.

3. The method of refining mineral lubricating oils which comprises treating said oils with an amount of sulfuric acid approximately equivalent to one-half to three-fourths pound of 93% sulfuric acid per gallon of oil, neutralizing said acid-treated oil with ammonia, and immediately extracting said neutralized oil with a selective solvent of the type used for separating paraffinic from naphthenic components, separating said paraffinic from said naphthenic components and removing solvent from each component.

4. The process of claim 1 wherein the selective solvent is dichlorethyl ether.

JAMES H. SHEPARD.
